UNITED STATES PATENT OFFICE.

WILLIAM EDWARD FORSTER, OF LAWRENCETOWN, NOVA SCOTIA, CANADA.

GUN-CLEANER.

SPECIFICATION forming part of Letters Patent No. 363,951, dated May 31, 1887.

Application filed January 26, 1887. Serial No. 225,594. (No model.)

To all whom it may concern:

Be it known that I, WILLIAM EDWARD FORSTER, of the town of Lawrencetown, in the county of Annapolis, in the Province of Nova Scotia, Canada, mechanic, have invented new and useful Improvements in Cleaners for Cleaning Breech-Loading Fire-Arms; and I do hereby declare that the following is a full, clear, and exact description of the same, reference being made to the accompanying drawings, in which—

Figures 1 and 2 are sectional views of the cleaners, the connecting cord being shown in side elevation.

Fig. 1 is a transverse section of one end. The cleaner is conical-shaped. The letter A indicates a screw-bolt, passing the entire length of this part of the cleaner and fastened on the base of the cone by a nut, while at the other end the rim of the bolt is attached to the cord marked D D.

The letter B indicates layers of leather, circular in form, which are placed on the screw-bolt as washers between the parts marked C C C. The letters C C C indicate circles of rubber, which are placed in the figure at the intervals indicated, and above each layer of leather. It is intended, also, that the letter B should indicate solid rubber, the circles C C C in that case being merely cut from such rubber.

Fig. 2 represents a transverse section of the other end of the cleaner. The letter A' indicates a screw-bolt, fastened at the outer end by a nut and at the other end attached to a snap-hook, F. The letter B' indicates leather circles passing around and attached to the screw-bolt A'. The letter E represents a sponge, which completely encircles the screw-bolt A', and is applied in rings on the latter, but so as to form one complete surface. The letter F represents a snap-hook passing through the eye of the screw-bolt A'. The letter G indicates a spiral-coil of lead for weighting the end

of the cleaner, Fig. 2. It passes around and is firmly attached to the cord marked D D. The letters D D indicate a cord connecting the two ends of the cleaner, Figs. 1 and 2.

The ends of the cleaner, Figs. 1 and 2, are intended to be of different sizes, according to the bore of the breech-loader.

The cleaner is used by saturating the end, Fig. 2, with water for washing the barrel, then detaching it and dropping the weighted end of the cord through the barrel, then reattaching the sponge and drawing it through. A rag or cloth, dry or saturated with oil, is then wound around the end, Fig. 1, the weighted end, Fig. 2, is dropped through the barrel, the sponge being first detached, and the end, Fig. 1, is then drawn through the barrel.

I claim as my invention and desire to secure by patent—

1. A cleaner for fire-arms, consisting of a porous sponging and a scraping head connected by a flexible cord, said cord being weighted at its extremities and detachably connected to one of the cleaner-heads.

2. A cleaner for fire-arms, consisting of a sponging and scraping head connected by a flexible cord, which is weighted at its extremities and detachably connected to one of the heads, the scraper consisting of a series of beveled disks, separated by interposed washers and clamped upon a rigid spindle, as set forth.

3. A cleaner for fire-arms, consisting of a scraper and sponging-head connected by a flexible cord having its extremities weighted and detachably connected at one end to one of the heads, the sponging-head consisting of a conical elastic body having a covering of sponge or like porous material, as set forth.

WILLIAM EDWARD FORSTER.

In presence of—

WILLIAM B. McKEOWN,

JOHN W. McKEOWN.
